UNITED STATES PATENT OFFICE

100,375

DESIGN FOR A LIQUID SPRAYER

Ivar Jepson, Chicago, Ill., assignor to Chicago
Flexible Shaft Company, Chicago, Ill., a cor-
poration of Illinois

Application April 22, 1936, Serial No. 62,242

Term of patent 7 years

To all whom it may concern:

Be it known that I, Ivar Jepson, a citizen of the United States, residing at Chicago, in the county of Cook and State of Illinois, have invented a new, original, and ornamental Design for a Liquid Sprayer, of which the following is a specification, reference being had to the accompanying drawing, forming part thereof.

In the drawing:

Figure 1 is a side view of a liquid sprayer showing my design, and

Figure 2 is a top view thereof.

I claim:

The ornamental design for a liquid sprayer substantially as shown.

IVAR JEPSON.
